NONREFILLABLE CAP FOR BOTTLES

Jay Dobkin, Laurelton, N. Y., assignor to Schenley
Industries, Inc., a corporation of Delaware

Application July 31, 1946, Serial No. 637,489

4 Claims. (Cl. 215—19)

1

This invention relates to a non-refillable cap for bottles, containers and the like.

Among the objects of the invention is the provision of a simple device adapted for effectively sealing a container, dispensing the contents thereof and preventing re-use or refilling of the container after it has once been emptied.

For the attainment of the above objects and such other objects as may hereinafter appear or be pointed out, I have illustrated two embodiments of the invention in the accompanying drawing, wherein:

Fig. 1 is a sectional view illustrating a cap embodying one form of the invention attached to a bottle which has been inverted and pressed down into a dispenser (not shown) carrying a pouring tube for draining off the contents of the bottle;

Fig. 2 is a sectional view similar to Fig. 1, illustrating the closed condition of the cap after the contents of the bottle has been emptied and the pouring tube removed, preventing refilling of the bottle;

Fig. 3 is a sectional view of the cap taken along line 3—3 of Fig. 4;

Fig. 4 is a vertical section of the cap showing a stopper or plug in place to seal the cap and retain the valve before use;

Fig. 5 is a view similar to Fig. 1 but showing a cap embodying another form of the invention;

Fig. 6 is a sectional view taken along line 6—6 of Fig. 5; and

Fig. 7 is a perspective view, with parts broken away, of the components of the cap illustrated in Figs. 5 and 6.

Referring first to the embodiment of my invention illustrated in Figs. 1—4 and particularly to Fig. 4, it will be seen that the non-refillable cap is formed with a skirt or collar portion 10 for attachment to a bottle and a downwardly projecting body portion 11 which enters the neck 12 of the bottle when the cap is affixed to the bottle.

A passageway 13 is provided in the body portion 11 extending longitudinally therethrough. The body portion 11 is also provided with a lateral recess 14 within which a valve 15 may be slidably mounted. A compression spring 16 disposed between the valve 15 and the inner end of the lateral recess 14 normally acts to urge the valve 15 outwardly to operative position (as shown in Fig. 2) closing or blocking the passageway 13. Fig. 4 also shows a stopper or plug 17 insertable within the passageway 13 to retain the valve 15 and seal the cap before use.

2

The assembly just described and shown in Fig. 4 is then cemented or otherwise permanently affixed to the neck 12 of the bottle in the position shown in Fig. 1 and Fig. 2. When the neck 12 of the bottle has an external thread, the collar portion 10 of the cap may be internally threaded for attachment to the bottle and then cemented or otherwise permanently affixed.

The bottle is inverted and pressed down into 10 a dispenser (not shown) carrying a pouring tube 18 which enters the passageway 13 in the cap within which the plug 17 is temporarily located. As the pouring tube 18, which preferably carries a longitudinal depression 19 to permit the entrance of air into the bottle, enters the bottle and assumes the position shown in Fig. 1, the plug 17 is pushed out of the cap and into the interior of the bottle, as shown in Fig. 1 and Fig. 2. The inserted pouring tube 18 retains the valve 15 in the inoperative position shown in Fig. 1.

The contents of the bottle can now be drained through the tube 18, air simultaneously entering the bottle through depression 19. When the bottle has been emptied, the tube 18 is removed.

25 As the tube 18 leaves the passageway 13, the valve 15 is urged outwardly by the spring 16 to the operative position, shown in Fig. 2, closing the passageway 13. It is then impossible to refill the bottle. The tube 18 is preferably attached to the dispensing apparatus so that when the empty bottle is pulled upwardly away from the dispensing apparatus, the tube 18 is automatically pulled out of the passageway 13 in the non-refillable cap.

35 Referring to the recess 14 in which valve 15 is slidably located, it will be noted that the right half section thereof is of greater diameter than the left half section thereof. In addition, valve 15 is of smaller diameter than the said right half section A of said recess 14. By reason of the foregoing, when said valve 15 is in the operative or closed position shown in Fig. 2, it is more difficult for any one to tamper with said valve through passageway 13. It becomes increasingly difficult for any one to move or return said valve 15 to its original inoperative position shown in Fig. 1, because any pressure upon the said valve immediately throws the same off center and it is then no longer possible for it to be returned to its original position within left half section B of recess 14.

40 Figs. 5—7 illustrate a non-refillable cap embodying another form of the invention. 45 In this embodiment the non-refillable cap is formed with a body portion 20 carrying an in-

50 55

ternally threaded collar portion 21 for attachment to the externally threaded neck 12 of a bottle. A passageway or hole 22 is provided in the body portion 20. The body portion 20 may have an annular groove 23 for receiving the lower end of a cylindrical valve chamber 24 which may be fastened to the body portion 20 by means of threads, press fit or in any other desired manner. A passageway or hole 25 carried by the base of the valve chamber 24 is aligned with the passageway or hole in the body portion 20.

Within the valve chamber 24 is pivotally mounted by means of pins 26 a rotary valve 27 having a longitudinal recess 28. A tensioning spring 29 having ends projecting in opposite directions is mounted on pin 26 with one end anchored in a small hole 30 in the rotary valve 27 and its other end anchored in a small hole 31 in the body portion 20. A stopper or plug 17 is insertable within the cap through the aligned passageways 22 and 25 in the body portion 20 and the valve chamber 24 respectively and the longitudinal recess 28 in the rotary valve 27 and when in position seals the cap and holds the rotary valve 27 in inoperative position. The tensioning spring 29 acts to rotate the valve 27 and to close the passageway through the cap defined by passageway 22, longitudinal recess 28 and passageway 25.

The cap assembly just described functions in the same manner as the cap initially described herein.

The cap assembly is screwed onto neck 12 of a bottle and then cemented or otherwise permanently fixed in the position shown in Fig. 5.

Similarly, the bottle is inverted and pressed down on a dispenser (not shown) carrying a pouring tube 18 which enters successively the passageway 22 in the body portion 20, the longitudinal recess 28 in the rotary valve 27 and the passageway 25 in the base of the valve chamber 24.

As the pouring tube 18 enters the bottle and assumes the position shown in Fig. 5, the plug 17 is pushed out of the cap and into the interior of the bottle. The inserted tube 18 holds the rotary valve 27 in the inoperative position shown in Fig. 5. The contents of the bottle can now be drained through the tube 18. After the bottle has been emptied, it is drawn off the tube 18. As the tube 18 passes out of the lower passageway 22 in the cap body portion 20, the valve 27 is rotated by the spring 29 and closes the passageway through the cap, thereby making it impossible to refill or re-use the bottle.

Since certain modifications in the non-refillable cap which embody the invention may be made without departing from its scope, it is intended that all matter contained in the above description or shown in the accompanying drawing shall be interpreted merely as illustrative and not in a limiting sense.

Having described my invention and illustrated its use, what I claim as new and desire to secure by Letters Patent is:

1. A non-refillable cap for bottles and like containers comprising a collar portion adapted for permanent attachment to the neck of the container, a body portion having a longitudinal passageway extending therethrough and a lateral recess therein, a spring-actuated valve member disposed within said recess and normally tending to close said passageway and a removable plug insertable within said passageway for retaining said valve member in its inoperative position.

2. A non-refillable cap for bottles and like containers comprising a collar portion adapted for permanent attachment to the neck of the container, a body portion having a longitudinal passageway extending therethrough and a lateral recess therein, a spring-actuated valve member slidably mounted within said recess and normally tending to close said passageway and a removable plug insertable within said passageway for retaining said valve member in its inoperative position.

3. A non-refillable cap for bottles and like containers comprising a collar portion adapted for permanent attachment to the neck of the container, a body portion integral with said collar portion, extending into the neck opening of the container, said body portion having a longitudinal passageway extending therethrough and a transversely-extending hole intersecting said passageway, a spring actuated valve member slidably mounted within said hole and normally tending to close said passageway, and a removable plug mounted within said longitudinal passageway and preventing said valve member from closing said passageway.

4. A non-refillable cap in accordance with claim 3 in which the transversely-extending hole is enlarged in the area of its intersection with the longitudinally-extending passageway, thereby providing a shoulder in said hole adjacent said longitudinal passageway, said shoulder providing a stop for the valve member after the valve member has been released into its normal position in the enlarged end of the hole, closing the longitudinal passageway to prevent said valve member from being pushed back into its non-operative position in the smaller end of the transverse hole.
